(57) **CLAIM**

The ornamental design for a mount accessory for an electronic device, as shown and described.

DESCRIPTION

FIG. 1 is a front isometric view of a mount accessory for an electronic device showing our new design;

FIG. 2 is a top view thereof;

FIG. 3 is a bottom view thereof;

FIG. 4 is a front view thereof; and,

FIG. 5 is a right view thereof.

The broken lines shown in the drawings represent portions of the mount accessory for an electronic device that form no part of the claimed design.
